UNITED STATES PATENT OFFICE.

ATLEE B. SAURMAN, OF PITTSBURGH, PENNSYLVANIA, ASSIGNOR TO STANDARD UNDERGROUND CABLE COMPANY, OF PITTSBURGH, PENNSYLVANIA, A CORPORATION OF PENNSYLVANIA.

TERMINAL FOR ELECTRIC CABLES.

Application filed December 17, 1924. Serial No. 756,374.

My invention relates to improvements in terminals for electric cables, and consists in a modification of structure, in consequence of which it becomes possible to fill the spaces within the terminal casing more expeditiously and more completely than hitherto has been possible. In consequence, I overcome defects and difficulties consequent upon faults of installation which in existing practice are of not infrequent occurrence.

I have worked my invention out in connection with a terminal of the particular construction shown and described in United States Letters Patent No. 1,159,655, granted November 9, 1915, on the application of Charles W. Davis, and, while it is not limited in adaptability to that construction alone, I shall here show and describe it so adapted.

In the accompanying drawings Fig. I is a view partly in side elevation, partly in longitudinal section, of a terminal in the construction of which my invention is embodied; Fig. II is a view in detail and to larger scale, on the same plane of section as that employed in Fig. I; and Fig. III is a view in transverse section, on the plane indicated at III—III, Fig. II, of a certain member of the structure there shown.

The terminal, as it is shown in Fig. I, includes a two-part thimble, consisting of a cable-receiving bell 1 and a lead-receiving fork 2. The bell 1 is adapted to be secured, as shown, by a wiped-solder joint to the cable-sheath; the fork 2 is provided in this instance with three sleeve-like projections 3. Thus the particular structure of the figure is one which is adapted to serve as the terminal for a three-conductor cable. The thimble parts may be suitably united, as by the screw-thread union shown.

A sleeve 4 of insulating material, ordinarily porcelain, is secured in each sleeve-like projection 3. The union is preferably effected by means of an exteriorly threaded ring of metal 5 permanently attached to sleeve 4 and engaging a corresponding interiorly screw-threaded surface at the edge of projection 3. The sleeve 4 is potticoated exteriorly, as indicated at 6, 7. The open-

ing through sleeve 4, the bore through the sleeve, is stepped, at 9.

A conducting stem 11 extends within the bore of sleeve 4. This stem is at its inner end so shaped as to be brought into electrical union with a bared cable conductor 13. Fig. II shows it to be socketed, at 33. At its outer end the stem is screw-threaded, and at an intermediate point in its length it is provided externally with a shoulder, adapted in assembly to engage the step 9 of the bore of the sleeve. Three nuts, 14, 34, and 18 are successively applicable to the outer screw-threaded end of stem 11. The outermost nut 18 is preferably a cap-nut. One at least of the two nuts 14 and 34 is formed of conducting material, and conveniently all three nuts are formed of conducting material. The first applied nut 14, abutting upon the outer end of sleeve 4, serves as a clamping member, to secure the stem 11 in position, with the shoulder formed exteriorly upon it in firm engagement with the stepped bore of sleeve 4. A ring 17 of conducting material, shaped to serve as a pole-piece for an aerial is by the nut 34 clamped to place against nut 14 and between surfaces so brought to contact electric union is completed.

When the parts are assembled the spaces within the structure are filled with insulating compound, applied in liquid condition. A filling hole such as has hitherto been employed, is indicated at 24, Fig. I.

It will be perceived in Fig. I that the projections 3 are of considerable extent, and that the sleeves 4 are prolonged within projections 3, in long-extending skirts 23. This skirted extension of the insulating sleeves is a feature of great practical importance. But in consequence there is formed, between conductor and sleeve, an extended, narrow, cylindrical space. Hitherto the filling of this space with insulating compound has been achieved only with relatively great difficulty, and imperfectly and uncertainly, so that in practice this is a point of weakness in the finished structure. Owing to the circumstances, that installation is usually made in the field, that the compound, applied hot,

loses fluidity when brought to contact with cold surfaces, and to the fact that the space between the conductors 11 and the sleeve 4 is a cul-de-sac, in which air may be trapped, to the exclusion of the flushing flood of insulating compound, proper filling is difficult, and, but for my invention, practically impossible to attain. Neither inversion of the structure nor the exertion of pressure upon the submerging flood of compound will overcome the difficulty, and insure satisfactory practice.

My invention consists in providing a filling tube, extending longitudinally through the lead-out structure, preferably in the form of a perforation through stem 11, longitudinally. Such a perforation is shown in the bore 25, extending from the outer end of stem 11. This perforation opens to the interior of the terminal casing, and to that end it preferably extends to a point at or immediately beyond the external shoulder upon stem 11, mentioned above. It there meets a cross bore 26, which leads through the body of stem 11 and opens to the cylindrical cavity formed by and between conductor and skirted sleeve.

A tube so placed may cooperate with a filling hole such as 24, Fig. I, and constitute an air escape, allowing the flood of compound to advance into the otherwise closed-ended cylindrical space between conductor and sleeve. Again the filling hole 24 may be dispensed with, and the tube may be made of such size as to allow both the introduction of compound to fill the whole space within the terminal casing and the coincident escape of air. Again, in a multiple-conductor installation, such as that shown in Fig. I, the filling hole 24 being dispensed with, the tube through one lead-out structure may constitute the filling hole and a similar tube through another of the lead-out structures, or through both of the other lead-out structures, may constitute openings for air escape. Preferably, however, and particularly in a terminal for a single-conductor cable, where there is but one lead-out structure, I form through the stem 11 two perforations, 25 and 27, terminating, at the point already indicated, in the cross-bores 26 and 28, as particularly shown in Figs. II and III. One of these, preferably of larger size, 25, with double-opening cross-bore 26 is designed for the pouring-in of compound; the other, of smaller size, 27, and with a single-opening cross-bore 28, is designed for the escape of air. These perforations 25 and 27 may also be intersected by cross-bores 30 and 31, arranged above the shoulder upon stem 11, in order to fill, if desired, the space surrounding stem 11 above the shoulder and below the nut 14.

Filling is achieved before the cap-nut 18 is for the last time applied. The filling com-

pound is introduced in obvious manner through perforation 25, while displaced air escapes through perforation 27, and the pouring in of compound continues until the terminal casing is completely filled, including the cylindrical space between conductor and sleeve, up to shoulder 9, and, if desired the space above shoulder 9 which surrounds stem 11, and including even the perforations 25 and 27 themselves. No tipping nor inverting of the structure is necessary to effect this. Pressure may be imposed on the entering flood of compound. After filling, the perforations may be closed in any suitable manner. The cap nut 18 itself is shown to be chambered and I show it to be provided with an orifice filled by a plug 29. The nut may be applied while the orifice is open, and if the operation of filling has not already been performed, it may be performed through such opening. Whether filling has been performed before or after the application of cap-nut 18, the space within the cap-nut itself is finally, filled. Filling being completed, plug 29 is secured in place.

The chamber within the cap-nut filled with insulating compound, constitutes then a reservoir, and this reservoir may be enlarged indefinitely, or supplemented, and by means known to the art, the body of compound within may be made effective, to maintain the terminal at all times and under all conditions filled with compound, and to prevent under any circumstances the opening of spaces or fissures within the terminal.

The stem 11 is shown to be provided, additionally, with a bore 32, opening to the socket at the lower end of stem 11, where the end of the bared cable conductor is introduced. Cable conductors are, particularly in large cables, usually stranded; in some cases they are hollow. And insulating compound passing through this bore may fill more effectively spaces which, incidentally to installation, may have developed in the conductor of the cable itself.

I claim as my invention:

1. A terminal structure for an electric cable including a casing provided with an orifice for an incoming cable and with a second orifice for a lead-out structure, a lead-out structure adapted to be set in the last-named orifice, such lead-out structure including a sleeve of insulating material with a stepped bore, and a shouldered stem of conducting material together with means for seating the stem in the bore of the sleeve with the shoulders in abutment, said stem being perforated by a duct penetrating the stem from its outer end and opening through the stem laterally at points both above and below the shoulder aforesaid.

2. A terminal structure for an electric cable including a casing provided with an orifice for an incoming cable and with a

second interiorly shouldered orifice for a end in a conductor-receiving socket, the stem lead-out structure, an exteriorly shouldered being further provided with a longitudinal lead-out structure adapted to be set in the perforation opening through the end of the 10 orifice last-named with the shoulders in abut-
ment, such lead-out structure including a sleeve of insulating material and a stem of conducting material terminating at its inner

In testimony whereof I have hereunto set my hand.

ATLEE B. SAURMAN.
